UNITED STATES PATENT OFFICE.

WALTER GREACEN, OF NEWARK, NEW JERSEY, ASSIGNOR TO HIMSELF
AND WILLIAM ROBOTHAM, OF SAME PLACE.

DESIGN FOR HARNESS-ROSETTES.

Specification forming part of Design No. 7,426, dated May 12, 1874; application filed March 20, 1874.
[Term of Patent 3½ years.]

To all whom it may concern:

Be it known that I, WALTER GREACEN, of Newark, New Jersey, have invented a Design for Rosettes for Harness, of which the following is a specification:

The nature of my design is fully represented in the accompanying photographic illustrations, to which reference is made.

A represents the base of the rosette, having an ornamental scalloped edge, B. To the top of this base is secured a spherical ball or button, C.

Having thus described my invention, I claim—

The design for a rosette, consisting of the base A, having an ornamental border, and a ball or button, C, substantially as shown and described.

WALTER GREACEN.
